UNITED STATES PATENT OFFICE.

THOMAS S. SCOTT, OF PITTSBURGH, PENNSYLVANIA, ASSIGNOR TO WESTINGHOUSE ELECTRIC & MANUFACTURING COMPANY, A CORPORATION OF PENNSYLVANIA.

COMMUTATOR FOR DYNAMO-ELECTRIC MACHINES.

1,075,502.

Specification of Letters Patent.

Patented Oct. 14, 1913.

Application filed December 14, 1908. Serial No. 467,463.

To all whom it may concern:

Be it known that I, THOMAS S. SCOTT, a citizen of the United States, and a resident of Pittsburgh, in the county of Allegheny 5 and State of Pennsylvania, have invented a new and useful Improvement in Commutators for Dynamo-Electric Machines, of which the following is a specification.

My invention relates to commutators for 10 dynamo-electric machines, and it has for its object to provide a simple device of this character which shall be specially adapted for use with machines to be operated at relatively high speeds, by steam turbines, or 15 otherwise.

When large machines of the commutator type are operated at high speeds, the devices usually employed for clamping the commutator bars in position are inadequate, by reason 20 of the very large centrifugal force to which the commutators are subjected. According to my present invention, I provide a plurality of rings which severally comprise a large number of turns of steel band 25 wire and are located either on the surface of the commutator cylinder or in annular grooves in said surface for the purpose of holding the bars or segments securely in position, the rings being suitably insulated 30 from the commutator cylinder to avoid short-circuiting the commutator bars.

Figure 1 of the accompanying drawings is a longitudinal section of one-half of a commutator cylinder constructed in accordance 35 with my invention, and Fig. 2 is an enlarged sectional view of one of the binding rings shown in Fig. 1. Fig. 3 is a view similar to Fig. 1 but illustrating a modification of my invention and Fig. 4 is a sectional 40 view of one of the binding rings shown in Fig. 3.

Referring to Figs. 1 and 2 of the drawings, the matter illustrated comprises an armature of a dynamo-electric machine having 45 a magnetizable core member 1, end rings 2, a supporting frame or spider 3 and a commutator cylinder 4. The commutator cylinder 4 comprises a cylindrical projection 5 of the spider 3, a plurality of bars 50 or segments 6 which are mounted on the surface of the cylinder 5 and are separated therefrom by a bushing 7 of insulating material. Each of the bars 6 is provided with a neck or connector 8 which extends radially outward from its inner end and with a

notch 9 at its outer end. When the bars are assembled, the notches 9 form a cylindrical projection 9^a at the outer end of the commutator cylinder, the diameter of which is somewhat less than that of the contact 60 surface of the cylinder. The bars 6 are held in position by rings 10 and 11 which encircle the cylinder, one being disposed adjacent to the necks 8 and the other being located on the cylindrical projection 9^a. The 65 rings 10 and 11 are separated from the bars 6 by strips 12 of insulating material and each of them comprises a metal ring 13 of U-shape in cross section, which may be split transversely or composed of a plurality of 70 segments, a large number of turns or convolutions 14 of steel band wire and a superposed metal ring 15, which may also be either split or of segmental structure, the edges of the ring 13 being bent inward to 75 hold the ring 15 in position. The splitting of either or both of the rings 13 and 15 or the dividing of them, or either of them, into a plurality of segments is a matter of 80 expediency in manufacturing and assembling, and neither structure is presented as a feature of patentable novelty. After the rings 10 and 11 are formed, as above indicated, each of them is provided with a wrapping 16 of insulating material which is overlapped on the outer cylindrical surface of the ring and is held in position by a layer of convolutions 17 of twine or cord, a final covering 18 being wrapped around the circumference of the ring on top of the cord 85 90 and held in position by sewing to the insulating wrapping 16. When the rings 10 and 11 are completed, they may be handled in the same way as a solid metal ring so that if it is desired to dismember the commutator, for any reason, the rings may be heated 95 until they expand sufficiently to be readily removed from the commutator cylinder. The rings 10 and 11 are preferably constructed by winding the necessary convolutions of 100 band wire upon the U-shaped rings 13 after the latter and the wrappings 16 have been placed in position upon the commutator cylinder. The sides of the metal rings 13 are preferably slotted to form fingers 13^a which 105 may be easily bent over the edges of the ring 15.

Referring to Figs. 3 and 4 of the drawings, commutator bars or segments 19 are mounted on a bushing 20 from which they 110

are separated by means of insulating rings 21. The bushing 20 is provided with an enlargement 22 having a frusto-conical outer surface, and a ring 23, having a similar outer surface, is mounted on the opposite end of the bushing. The position of the ring 23 may be varied by means of an adjusting nut 24 which is screwed upon the outer end of the bushing 20. The inner edges of the bars or segments 19 are adapted to fit against the frusto-conical surface provided by the enlargement 22 and the ring 23 and the segments are of wedge shape in cross section so that they may be readily assembled to form a cylindrical commutator structure, in the usual manner. The commutator cylinder is provided with a plurality of annular grooves 25 which are intended to receive sufficient turns 26 of steel band wire to hold the bars in position. The walls of the grooves are first insulated by means of rings 27 of U-shape in cross section. A similar ring or casing 28 of sheet brass is fitted into the insulating ring 27, the band wire being disposed within the brass casing which is intended to prevent injury to the insulation by the band wire. After the band wire is wound upon the brass rings, the casing is closed by bending the edges of said rings over a cover strip 29, an insulating strip 30 being held in position by any suitable means such as a layer of twine 31. By properly designing the

grooves 25 to receive the necessary band wire and insulation, the surface of the insulating twine may be substantially flush with the cylindrical surface of the commutator. It will, of course, be understood that the parts 27, 28, 29 and 30 will be severally split transversely or composed of a plurality of segments in order that they may be assembled in the grooves 25.

I desire that structural modifications which do not depart from the spirit of my invention shall be included within its scope. 45

I claim as my invention:

1. A commutator comprising a plurality of bars or segments and a plurality of clamping rings therefor, each of which comprises convolutions of wire, a sheet metal 50 casing for the wire and an insulating casing for the sheet metal.

2. A commutator comprising a cylindrical bushing, a plurality of bars or segments mounted thereon and insulated therefrom and a plurality of composite clamping rings 55 each of which comprises convolutions of wire, a metal armor therefor and an insulating jacket for the metal armor.

In testimony whereof, I have hereunto 60 subscribed my name this 30th day of Nov., 1908.

THOS. S. SCOTT.
